UNITED STATES PATENT OFFICE.

JOHN W. SEIFERT, OF COLUMBUS, GEORGIA.

GIN-FEEDER AND SEPARATOR.

SPECIFICATION forming part of Letters Patent No. 727,700, dated May 12, 1903.

Application filed December 23, 1902. Serial No. 136,376. (No model.)

To all whom it may concern.

Be it known that I, JOHN W. SEIFERT, a citizen of the United States, residing at Columbus, in the county of Muscogee, State of Georgia, have invented certain new and useful Improvements in Gin-Feeders and Separators, of which the following is a specification, reference being had therein to the accompanying drawings.

10 This invention relates to a cotton-gin feeder, and particularly to an improved construction of bat-forming mechanism and a separator to remove from the picked cotton any foreign substance remaining therein.

15 The invention has for an object to provide an improved construction of bat-former comprising a feed-roller, a bat-forming roller, and a picker-roller coöperating with a screened surface extending concentrically 20 therewith.

25 A further object of the invention is to provide a separator comprising a series of rolls driven at successively different speeds and spaced from each other to permit the fall of foreign substances from the picked cotton as it passes over these rolls.

30 A further object of the invention is to provide an improved construction of driving mechanism for coöperatively actuating the several movable parts in order to secure the proper feed of the cotton through the machine.

35 Other and further objects and advantages of the invention will be hereinafter set forth and the novel features thereof defined by the appended claims.

In the drawings, Figure 1 is an elevation of one end of the gin-feeder; Fig. 2, a similar view of the opposite end; Fig. 3, a central 40 vertical section through the same; and Fig. 4, a detail longitudinal section through the feeding-roller.

Like letters of reference refer to like parts in the several figures of the drawings.

45 The letter A designates a casing, which may be of any desired construction, having a feed-opening A' at its upper portion and a dirt-discharge A² at one side thereof, while a cotton-discharge chute A³ is disposed at the opposite 50 side and from which the clean material falls into the gin. Beneath the feed-opening A' a feed-roller B, provided with teeth or spikes

B' upon its periphery, is mounted in the casing by means of its shaft B². At one side of this feed-roller a bat-forming roller C is provided and has upon its periphery a series of teeth C', preferably extending radially therefrom and mounted in the casing A by means of its shaft C². Beneath the bat-forming roller C a picker-roller D is disposed and provided with peripheral teeth D', extending radially therefrom, while the roller is mounted in the frame by means of the shaft D². Concentric to this picker-roller is a screen D³, which may be of any desired construction, though preferably formed of longitudinally-extending slats spaced apart the proper distance to permit the passage between the same of cotton-stems or other matter which it is desired to liberate from the cotton as it passes between the screen and picker-roller. This screen extends from the partition D⁴ at one side of the bat-former C to the plate D⁵ at the opposite side of the picker-roller D, and the material discharged over said plate passes through the discharge-chute A³ and over the series of separator-rolls E. In order to secure the most desirable feed in the gin, the teeth upon the feed-roller B are made of greater length at each end, as shown at B³, and gradually decrease in length toward the center of the roller. The object of this is to produce a heavier or larger feed at the ends of the roller, as better results are thus secured in the subsequent action of the gin upon the cotton fed thereto. The dirt and material passing through the slatted screen D³ falls down the chute A³ and is conveyed therefrom by any suitable form of conveyer, as shown at A⁴.

The separating-rolls E are each provided with a smooth surface and are spaced apart a sufficient distance to permit any foreign matter carried by the picked cotton to fall by gravity between the rolls. The shafts E' of each of these rolls are suitably mounted in the sides of the chute A³, and the rolls are each rotated in the same direction, but at an increasing speed, so that the cotton in passing thereover will be picked up by the roller in advance and carried thereover onto the next roller, and thus prevented from passing downward between the rollers, while the cotton being in a picked or open condition any

foreign matter—such as hulls, nails, gravel, or other substances liable to injure the ginsaws—will fall by gravity and be caught in the box or casing A⁵, disposed beneath the 5 separator-rolls and can be removed therefrom by means of the door A⁶, as shown in Fig. 3.

For the purpose of driving the several movable parts of the mechanism a driving-wheel F may be secured to the shaft D² of the picker- 10 roller, which shaft will also carry a friction-wheel F', adapted to engage the periphery of a similar wheel F², mounted upon the angle-arm F³ of the lever F⁴, which is pivotally mounted upon the casing at F⁵. The friction-wheel F² also carries a sprocket-gear F⁶, 15 from which a suitable chain F⁷ extends over the series of sprockets F⁸, F⁹, and F¹⁰, disposed upon the shafts E' of the separating-rolls. These sprockets are of successively 20 smaller diameter, so that by the passage of the chain thereover the rolls driven thereby will be given successively greater speeds of rotation. By means of the lever F⁴ the friction-wheel F² may be thrown out of engagement 25 with its coöperating member F' and the rotation of the separator-rolls thus stopped, while this lever may be normally drawn downward to throw and hold the friction-wheels together by means of a spring G. It can also 30 be engaged and held in its proper position to separate the wheels by means of a catch G'.

The shaft H, upon which the friction-wheel F² is mounted, is extended through the casing to the opposite end of the machine, said 35 casing being suitably slotted to permit the oscillatory movement of the shaft, and the opposite end of the shaft is provided with a friction-roller H', supported in a bracket H² and adapted to engage a disk H³, normally 40 held in contact therewith by means of a spring H⁴, extending between the disk and the bearing H⁵, through which the shaft H⁶ of the friction-disk passes. This shaft is provided at its opposite end with a worm-gear H⁷ and 45 a contact-plate H⁸, adapted to be engaged by a lever H⁹, pivotally mounted upon the end of the machine and provided with a handle H¹⁰, by means of which the shaft H⁶ may be shifted longitudinally to withdraw the friction-disk from contact with the roller H'. Meshing with the worm H⁷ is a pinion I, carried upon the shaft B² of the feed-roller, and the opposite end of this shaft is provided with a similar pinion I', meshing with a pinion I² 55 upon the shaft C² of the bat-forming roller, thus providing means for driving these several rollers at the proper relative speed of rotation.

In the operation of the invention it will be 60 seen that the cotton fed upon the feed-roller B will be carried thereby toward the bat-forming roller C, from whence it will be removed by the teeth of the picker-roller, which separates and opens the cotton, so as to permit the escape therefrom of dirt, hulls, and other refuse as it passes between the picker-roller and the concentric slatted screen. The

graduated teeth upon the feed-roller produce a heavier feed at each end thereof and a consequently more efficient service in the gin, 70 while the slatted screen permits the escape of a larger percentage of the refuse than ordinarily. The cotton when fed from the picker-roller passes upon the separator-rolls, between which the foreign matter contained 75 in the cotton is adapted to fall, and by rotating each of these rolls faster than the successive one the cotton, which would otherwise be carried downward by the other roller, is immediately picked up and thrown onto the 80 next roller, thus performing the work of a huller-gin and preparing the cotton for direct introduction into the gin without danger or injury to the saws thereof. These rolls are 85 rotated at any suitable high rate of speed and may be driven by any desired mechanism. These rolls also improve the condition of cotton fed into the gin, as if a bunch or lump occurs the movement of the rolls separates it and produces an even feed into the 90 gin.

It will be obvious that changes may be made in the details of construction and configuration without departing from the spirit of the invention as defined by the appended 95 claims.

Having described my invention and set forth its merits, what I claim, and desire to secure by Letters Patent, is—

1. In a gin-feeder, a casing, a toothed bat-forming roller, a toothed picker-roller beneath said forming-roller and coöperating with the teeth thereof, and a toothed feed-roller at one side of and opposite both bat-former and picker-roller to feed material between the same; substantially as specified. 100

2. In a gin-feeder, a casing, a toothed feed-roller, a toothed bat-former at one side thereof, a toothed picker-roller beneath said former, a cotton-discharge chute from said 105 picker-roller, and separator-rolls rotatably mounted therein and spaced from each other; substantially as specified.

3. In a gin-feeder, a casing, a toothed feed-roller, a toothed bat-former at one side thereof, a toothed picker-roller beneath said former, a cotton-discharge chute from said 115 picker-roller, separator-rolls rotatably mounted therein and spaced from each other, and means for rotating said rolls at successively 120 higher speeds; substantially as specified.

4. In a gin-feeder, a casing, a toothed feed-roller, a toothed bat-former at one side thereof, a toothed picker-roller beneath said former, a cotton-discharge chute from said 125 picker-roller, separator-rolls rotatably mounted therein and spaced from each other, means for rotating said rolls at successively higher speeds, a collecting-chamber beneath said rolls, a slatted screen concentric to one side of the picker-roller, and a dirt-chute beneath said screen; substantially as specified.

5. In a gin-feeder, a casing having a top opening, a feeder-roller beneath the same

having teeth decreasing in length from the ends toward the center thereof, a bat-forming roller, and a toothed picker-roller coöperating therewith and with the feed-roller; 5 substantially as specified.

6. In a gin-feeder; a feed-roller, a bat-former, a picker-roller, a cotton-discharge chute therefrom, and separator-rolls disposed in said chute and having smooth peripheries spaced from each other; substantially as specified.

7. In a gin-feeder, a feed-roller, a bat-former, a picker-roller, a cotton-discharge chute therefrom, separator-rolls disposed in 15 said chute and having smooth peripheries spaced from each other, sprocket-wheels of different diameters upon the shafts of said rolls, and a driving-chain engaging said sprocket-wheels; substantially as specified.

20 8. In a gin-feeder, a feed-roller, a bat-former, a picker-roller, a cotton-discharge chute therefrom, separator-rolls disposed in said chute and spaced from each other, sprocket-wheels of different diameters upon 25 the shafts of said rolls, a driving-chain engaging said sprocket-wheels, a driving-shaft carrying a friction-wheel thereon, a lever-arm provided with a counter-shaft carrying a co-operating friction driving-wheel, and a 30 sprocket-wheel carried by said friction driving-wheel adapted to drive said chain; substantially as specified.

9. In a gin-feeder, a feed-roller, a bat-former, a picker-roller, a cotton-discharge 35 chute therefrom, separator-rolls disposed in said chute and spaced from each other, sprocket-wheels of different diameters upon the shafts of said rolls, a driving-chain engaging said sprocket-wheels, a driving-shaft 40 carrying a friction-wheel thereon, a lever-arm provided with a counter-shaft carrying a co-operating friction driving-wheel, a sprocket-wheel carried by said friction driving-wheel adapted to drive said chain, a friction-roller

upon the opposite end of said counter-shaft, 45 an angularly-disposed shaft carrying a disk to contact with said roller, a driving-worm upon said shaft, a gear upon the shaft of the feed-roller engaging said worm, a gear upon the opposite end of the feed-roller shaft, and 50 a coöperating gear carried by the bat-former shaft; substantially as specified.

10. In a gin-feeder, a feed-roller, a bat-former, a picker-roller, a cotton-discharge chute therefrom, separator-rolls disposed in 55 said chute and spaced from each other, sprocket-wheels of different diameters upon the shafts of said rolls, a driving-chain engaging said sprocket-wheels, a driving-shaft carrying a friction-wheel thereon, a lever-arm 60 provided with a counter-shaft carrying a co-operating friction driving-wheel, a sprocket-wheel carried by said friction driving-wheel adapted to drive said chain, a friction-roller upon the opposite end of said counter-shaft, 65 an angularly-disposed shaft carrying a disk to contact with said roller, a driving-worm upon said shaft, a gear upon the shaft of the feed-roller engaging said worm, a gear upon the opposite end of the feed-roller shaft, a co- 70 operating gear carried by the bat-former shaft, a spring for retaining said friction-disk in contact with its roller, a head at the opposite end of the disk-shaft, and means for engaging said head to reciprocate said disk-shaft; substantially as specified. 75

11. In a gin-feeder, a bat-former, a picker-roller adapted to receive cotton from the bat-former, and means for feeding a greater amount of cotton to the ends than to the mid- 80 dle of the picker-roller and bat-former; substantially as specified.

In testimony whereof I affix my signature in presence of two witnesses.
